UNITED STATES PATENT OFFICE.

THOMAS NORGE, OF CHICAGO, ILLINOIS.

ENVELOP.

No. 921,275.

Specification of Letters Patent.

Patented May 11, 1909.

Application filed July 25, 1907. Serial No. 385,498.

To all whom it may concern:

Be it known that I, THOMAS NORGE, a subject of the Czar of Russia, and a resident of Chicago, in the county of Cook and State 5 of Illinois, have invented certain new and useful Improvements in Envelops, of which the following is a clear, full, and exact description.

My invention relates to envelops and particularly to the kind in which the inner surface of the envelop is adapted to be written upon before the envelop is folded and sealed.

The object of my invention is to provide an envelop which is designed to be folded by 15 the user and sealed without the use of gum or mucilage in such manner that it cannot be opened without tearing it and when thus opened cannot be again sealed. This I accomplish by the means hereinafter fully described and as particularly pointed out in the 20 claims.

In the drawings:—Figure 1 is a plan view of my improved envelop opened. Fig. 2 is a perspective view showing the first fold of the 25 envelop. Fig. 3 is a similar view showing the second fold. Fig. 4 is a similar view showing the third fold. Fig. 5 is a similar view showing the fourth fold. Fig. 6 is a detail view of the locking or sealing devices of 30 my invention.

My improved envelop is made from a substantially square piece of paper or other suitable material, which is folded by two longitudinal creases *a*, *a*, so as to produce three 35 equal transverse folds, and two transverse creases *b*, *b*, so as to produce three equal longitudinal folds, and form nine corresponding square divisions, the central one of which, *A*, constitutes the front of the envelop, and the 40 remaining surrounding divisions are adapted to be folded over back of the central square *A* in such manner as to form the back of the envelop and afford a support for the sealing and locking devices of the same. The 45 square corner divisions *B*, *C*, *D*, and *E* are each given a diagonal crease *c* that extends in alinement with the diagonals of the envelop blank and is bent or convexed toward the front surface of the same. The square divisions *F*, *G*, *H* and *I*, located between said corner divisions, are each provided with diagonal creases *d* that extend from the right hand corner of the central division *A* to the outer left-hand corners of their respective di-

visions to the edge of the blank which divisions are bent or convexed toward the rear of said blank.

The means for locking the envelop consists of a suitable staple *k* secured diagonally across the back of square *E* near its outer corner, and a clip *f* secured on the face of square *B* and extending in a direction at right angles to that of staple *k*. The portion of this clip that engages the staple consists of two overlapping portions (as shown in Fig. 6 60 of the drawings) that press toward each other and when said staple has passed between the same to lock and seal the envelop it is impossible to release the same from the exterior.

Now in order to form the back of the envelop section *B* is folded flat over section *F* and then the outer triangle of sections *B* and *F* is bent on the lines of creases *c* and *d* back over the front of the latter, *F*. This action 70 brings the half of section *I* adjoining section *B* over the central section *A*, and causes the half of said section *I* next section *E* to fold back on the line of crease *d*, over the first mentioned half section thereof and in this 75 position, when section *C* is folded over section *G*, said sections *B* and *F* will fold over the central section outside of section *I*. The outer triangle of sections *C* and *G* is then 80 bent on the lines of creases *c* and *d* back over the front of *G*, and then said last mentioned sections are folded on the line of crease *b* over the central section outside of sections *I*, *B* and *F*. When making this last fold section *D* folds over in front of section *H*, as shown in 85 Fig. 4, and then the outer triangles of the same are folded on the line of the creases *c* and *d* back over section *H* and then the two sections are folded over the central sections outside of the previously folded sections *C* 90 and *G*. This last fold causes section *E* to fold upon itself on the line of crease *c'* thereof and forms a triangular shaped flap, substantially as shown in Fig. 5 of the drawings, 95 which has the staple *k* on its front surface. This outer flap section *E* is then folded over the back of the envelop and its point tucked under sections *B* and *F*, until staple *k*, which 100 will be at right angles to the lapping ends of the metal clip is pushed beyond the extremity of the outer flap, whereupon said flap is drawn out slightly and the staple moves under said outer end and until it 105

moves past the inner lapped end of the strip, whereupon the envelop will be effectually sealed.

In order to assist in opening the envelop 5 after it is sealed I have provided section E with a straight series of perforations K which intersect the center of length of crease c' at right angles. When the envelop is sealed, flap section E can be torn off on the 10 line of these perforations and the envelop easily opened.

If desired the lock strip and the staple 15 may be omitted and the envelop simply folded in the manner explained and closed by flap-section E as shown and thus comply with the postal regulations concerning open letters.

An epistle written on separate note or letter paper may be folded and inclosed within 20 my improved envelop, but if desired the inside of the envelop blank may itself be written upon either ruled or not to suit the taste.

I do not desire to be confined to the placement of the lock-strip and staple as hereinbefore set-forth as there are other positions in which they may be located and seal the envelop, although not so effectually or securely as in the positions indicated, in which the envelop 25 cannot be opened without tearing or mutilation to such an extent as to make detection positive.

What I claim as new is:—

1. An envelop comprising a rectangular sheet folded into a series of rectangular sections, each of said sections adjacent to the outer edges of the sheet being provided with a diagonal crease, perforations extending 30 across a corner section at an angle to the crease thereon, said sections being folded

upon each other and diagonally upon themselves, and the perforated section having a portion thereof inserted between the folds of two adjacent sections.

2. An envelop comprising a rectangular 45 sheet folded into a series of rectangular sections, a two piece locking device one member of which is secured to one corner section and the opposite member of which is secured to another section, each of the sections adjacent to the outer edges of said sheet being provided with a diagonal crease and folded upon each other and diagonally upon themselves, and the locking corner section having a portion 50 thereof inserted between the folds of two adjacent sections whereby the parts of said locking device engage each other.

3. An envelop comprising a rectangular sheet folded into a series of rectangular sections, each of the sections adjacent to the outer edges of the sheet being provided with a diagonal crease, perforations extending 55 across a corner section at an angle to the crease thereon, a two piece locking device one member of which is secured to said perforated section and the opposite member of which is secured to another section, said creased sections being folded upon each other and diagonally upon themselves, and said locking corner section having a portion 60 thereof inserted between the folds of two adjacent sections whereby the parts of said locking device engage each other.

In testimony whereof I have hereunto set my hand and seal this 20th day of July, A. D., 75 1907.

THOMAS NORGEELL. [L. s.]
